CLAIM

The ornamental design for a luminaire, as shown and described.

DESCRIPTION

FIG. 1 is a top front perspective view of the luminaire of the present invention;

FIG. 2 is a front elevation view thereof;

FIG. 3 is a rear elevation view thereof;

FIG. 4 is an enlarged right side elevation view thereof;

FIG. 5 is an enlarged left side elevation view thereof;

FIG. 6 is a top plan view thereof;

FIG. 7 is a bottom plan view thereof; and,

FIG. 8 is a bottom rear perspective view thereof.

The broken lines shown are included for the purpose of illustrating environmental structures and form no part of the claimed design.
